A. H. Pease,*

UNITED STATES PATENT OFFICE.

JOHN ASHWORTH, OF SOMERVILLE, MASSACHUSETTS.

COVERED ELASTIC ENDLESS BAND.

SPECIFICATION forming part of Letters Patent No. 409,001, dated August 13, 1889.

Application filed May 11, 1881. Serial No. 33,027. (No model.)

To all whom it may concern:

Be it known that I, JOHN ASHWORTH, a citizen of the United States, residing at Somerville, in the county of Middlesex and State of Massachusetts, have invented a new and useful Covered Elastic Endless Band; and I do hereby declare that the same is fully described in the following specification and illustrated in the accompanying drawings.

10 My invention consists in an extensible band composed of an endless elastic core and a seamless fibrous envelope formed thereon capable of elongation and contraction with said core and forming an ultimate stop or limitation upon the elongation of said core.

It also consists in an elastic endless band formed of two or more separately covered elastic endless strands united laterally, as herein set forth.

20 Elastic endless bands of india-rubber or its compounds are common, and endless bands not elastic have long been known and used in connection with woolen machinery. Elastic cords not endless, covered with a fibrous braided cover, are also well known; but I am not aware that an endless band of elastic material covered with a flexible seamless and endless envelope has been produced prior to my invention thereof.

30 The drawings represent, in Figures 1 and 2, elastic bands made in accordance with my invention, Figs. 3 and 4 showing transverse sections of the single and triple bands shown in Figs. 1 and 2, respectively.

35 *a* denotes the endless rubber or elastic core, and *b* the covering inclosing it, while *c* represents the connecting stitches or threads that unite the parallel covered strands.

40 The core *a* is of india-rubber or its compounds, properly vulcanized, and is molded or cut into rings of circular, square, or flat section in a manner well known. These endless strands are then covered either by winding yarns or threads of various kinds spirally 45 in either direction or opposite directions around the single endless strand, or by braiding, interweaving, crocheting, netting, or knitting, by hand or machinery, a seamless and unwrinkled covering or envelope therefor, in such a manner as to permit of elongation and contraction of both core and covering together.

The spiral or zigzag arrangement of the

threads of the cover makes it extensible in length and contractile in diameter to correspond with the like changes of form of the rubber core when it is stretched lengthwise, thus maintaining a firm and symmetrical appearance, and since there is no real elasticity in the threads of the covering itself they will finally limit the extensibility of the complete 55 band, and thus protect the elastic core from overstraining, while at all times protecting it from lateral wear and from direct contact with the article embraced by the band.

60 The winding is several times repeated at a uniform feed, so as to form a complete covering, concealing the core and hiding the beginnings of the cover. The ends of the threads are drawn through and merged with those previously laid.

65 I furnish these bands for use as springs and for armlets, stocking-supporters, or any purpose where a protected elastic band may be advantageous. The triple band shown in Fig. 2 has its three separately wound strands 70 united laterally into one by any convenient stitch formed during or subsequent to the winding and not interfering with the elasticity of the band.

75 My improved bands may be covered by hand or by the use of any machinery adapted thereto, as I do not limit myself to any particular means of applying said coverings.

I claim as my invention—

80 1. An extensible band composed of an endless elastic core and a seamless endless flexible covering formed thereon of continuous threads, substantially as and for the purpose set forth.

85 2. An improved article of manufacture, 85 an elastic endless band formed of two or more parallel elastic endless strands, each having an extensible, flexible, seamless, and endless covering formed upon it, such separately-covered strands being united laterally into one 90 endless elastic covered band, substantially as set forth.

95 In testimony whereof I hereto affix my signature in presence of two witnesses.

JOHN ASHWORTH.
